UNITED STATES PATENT OFFICE.

ALBERT NELSON ALEXANDER, OF BERGENFIELD, NEW JERSEY.

SPARK-PLUG.

1,313,040.

Specification of Letters Patent. Patented Aug. 12, 1919.

Application filed August 24, 1917. Serial No. 188,005.

To all whom it may concern:

Be it known that I, ALBERT N. ALEXANDER, a citizen of the United States, and a resident of Bergenfield, in the county of Bergen 5 and State of New Jersey, have invented a new and Improved Spark-Plug, of which the following is a full, clear, and exact description.

This invention relates to spark plugs for 10 internal combustion engines or similar devices and has particular reference to the construction of spark plugs with respect particularly to the core of insulation commonly used in such a device.

15 Among the objects of the invention, therefore, is to provide a spark plug from which porcelain or the like is eliminated and for which I substitute a core of mica or its equivalent. While I am aware that it is not 20 broadly new with me to employ mica as a packing or insulation for spark plugs, yet I have devised a special form of core as will be set forth more fully hereinafter.

Another object of the invention is to provide 25 a novel type of adjustable ignition contact member in the nature of a thimble screw threaded into the inner end of the body of the plug and having at its inner end a central hole surrounded by a non-corrodible sleeve and having at its inner end a circular series of deep notches with which 30 co-operates a locking member held in place by the body of the engine into which the plug is fitted.

35 With the foregoing and other objects in view the invention consists in the arrangement and combination of parts hereinafter described and claimed, and while the invention is not restricted to the exact details of 40 construction disclosed or suggested herein, still for the purpose of illustrating a practical embodiment thereof reference is had to the accompanying drawings, in which like reference characters designate the same parts 45 in the several views, and in which—.

Figure 1 is a vertical central sectional view of my improvement in operative position.

Fig. 2 is a transverse sectional detail on 50 the line 2—2 of Fig. 1.

Fig. 3 is a similar view on the line 3—3.

Fig. 4 is a plan view of the contact thimble showing especially the notches; and

Fig. 5 is a detail perspective view of a 55 washer used in the outer end portion of the device.

Referring now more particularly to the drawings I show a spark plug comprising a metal body 10 screw threaded at 11 for co-operation with the engine body 12 as usual. 60 This body 10 as heretofore is hollow and adapted to carry within the central portion thereof and spaced from the middle of the body a contact pin 13 having at its inner end a contact point 14 and having its outer 65 end screw threaded for the accommodation of lock washers 15 and 16, and binding nut 17. One branch of the electric circuit, not shown, is adapted to be connected either between the nut 17 and the washer 15 or 70 snapped directly upon the nut 17 in the groove 17 thereof.

Tapped into the inner end of the plug body 10 is a contact thimble 18 having a peripheral flange 19 provided with a series 75 of equally spaced notches 20 and provided with a hub 21 having direct co-operation with the threaded end of the plug 10. The upper or inner edge of the hub 21 is provided with a series of equally spaced notches 80 22, one for each notch 20 and in the same radial plane thereof. See Fig. 4. I show by way of example a construction in which I employ five of these notches 22 and I suggest that the threads connecting the 85 thimble with the plug body 10 be made twenty per inch.

23 indicates a locking member shown as a screw tapped through the externally threaded portion 11 of the plug 10, the axis of the 90 screw being arranged at an angle of about thirty degrees to the axis of the contact pin 13. The inner end or point of the screw 23 is adapted to be located in any one of the notches 22 while the outer or head end of 95 the screw lies within the threaded surface at 11 and embraced by the body 12 of the engine when in operative position. The contact sleeve 24 carried in the center of the inner end of the thimble constitutes the 100 contact member co-operating with the contact point 14. This sleeve is made preferably of nickel or some similar non-corrodible material and is adjustable toward or from the contact point 14 by movement of the 105 thimble up or down with respect to the body 10, the adjustment being made secure by means of the screw 23. If the threads of the thimble be twenty per inch and there be employed five of the notches 22, it follows that 110 the design provides for an adjustment of the contact thimble in hundredths of an inch.

This adjustment is effected when the plug 10 is removed from the engine body so that the screw 23 may be withdrawn from the notches 22. The notches 20, however, formed 5 in the periphery of the flange 19 serve not only as a means for facilitating the rotation of the thimble, but as indicating means to show the operator when a notch 22 registers with the screw, this indication being 10 effective by alining a notch 20 with the outer end of the screw.

In place of the porcelain core that is commonly used in spark plugs and which is so apt to become broken or cracked and hence 15 render the spark plug useless, especially in high powered engines such as are used in aeroplanes, I employ a core the main portion of which consists of a roll or rolls of mica 25. The contact pin 13 is provided at about 20 its central portion within and spaced from the middle of the body 10 with an enlargement 13' in the nature of a frustum of a cone, but with convex sides. The inner surface of the body 10 opposite and spaced 25 from this concial enlargement is of practically the same form or parallel to said enlargement. The upper end of the body 10 is recessed at 26 or surrounded by a small 30 upstanding flange 27, the flange being re- mote from the inner surface of the body 10 whereby the recessed portion 26 constitutes a seat or shoulder. The roll of mica 25 em- 35 braces all of the enlargement 13' and extends both above and below the same and is so designed as to snugly fill the space between the enlargement and the inner wall of the body. Below the enlargement, however, there are provided a pair of spaces 28 and 29. The space 28 immediately surrounds the 40 inner end of the contact pin while the other space 29 lies between the roll of mica 25 and the body 10 of the plug. The contact pin therefore is well spaced and insulated from the metal body 10.

45 30 indicates a mass of mica in the nature of flat disks or washers surrounding the outer cylindrical end portion of the core 25 and the contact pin 13. The lower or inner end washers 30 are seated in the recess 26 and 50 within the flange 27 and all of these washers 30 are fitted closely upon the roll of mica 25. The disks or washers of mica are co- extensive, as a mass, with the outer end of the core and against the outer element of 55 the same is located the lock washer 15. The inner lock washer 16 is fitted upon the threaded end of the contact pin and lies against the upper or outer end of the core and within a recess in the inner or lower 60 face of the washer 15. This washer 16 is preferably of the split spring type so as to assist in holding the same in position when

the washer 15 is turned down thereupon. When the washers 15 and 16 are turned 65 snugly down upon the outer end of the mica 25 and 30 the conical or enlarged portion 13' of the contact pin is drawn snugly into wedging position serving to lock the core in fixed position within the body 10 of the spark plug. If desired the outer surface of 70 the enlargement 13 may be rough or knurled at 13' to increase the grip upon the mica.

A spark plug made in accordance with this invention is absolutely leak proof and heat resisting and consequently it cannot be 75 short circuited by oil or grease which is so likely to accumulate in the crack of a split or broken porcelain core. Furthermore the core is automatically self cleaning with respect to soot and carbon and can 80 easily be adjusted as to the spark gap to accommodate it to any magneto which may be employed to generate the ignition spark. Again, the mica core is of such a nature that it cannot be destroyed either by heat or the 85 explosion within a cylinder.

I claim:

1. A spark plug, comprising a hollow metal body having a portion of its inner surface tapered and having at its outer end 90 an annular recess, a roll of mica fitted within the tapered portion of the body and extending beyond the outer end of the body, a series of flat mica washers surrounding said 95 extending end of the roll of mica and seated in said recess, a contact pin projecting through the mica core and having a tapered enlargement fitted within the said core, means coöperating with the outer end of the 100 contact pin and bearing against the outer end of the series of mica washers to hold the parts all in firmly united condition and a thimble screwing in the outer end of the body and provided with a contact sleeve.

2. A spark plug, comprising a hollow 105 body having a portion of its inner surface tapered and having at its outer end an annular recess, a roll of mica in the body and projecting beyond the outer end of the body, a series of flat mica washers surrounding the 110 projecting end of the mica roll, the inner washers being seated in the recess of the body, a contact pin having its outer end threaded and extending through the mica roll, the pin being provided intermediate of 115 its ends with a tapered enlargement, the mica roll being spaced from the inner ends of the body and pin, washers on the projecting end of the pin and engaging the mica roll and disks, a nut on said end, a thimble 120 adjustably secured to the inner end of the body and carrying a contact.

ALBERT NELSON ALEXANDER.
